NEUTRALIZED POWER AMPLIFIER

Dale Pollack, Haddon Heights, N. J., assignor to
 Radio Corporation of America, a corporation
 of Delaware

Application September 30, 1938, Serial No. 232,482

1 Claim. (Cl. 179—171)

The present invention relates to neutralized power amplifiers, and has for an object to provide an improved neutralized power amplifier wherein an amplifier tube and a phase shifting network are included in the neutralizing circuit thereof, thereby to simplify the neutralizing circuit.

The invention may be embodied in any suitable signal amplifying channel including an amplifier tube having a predetermined grid-plate capacity in connection with a phase shifting network interposed in said channel with said tube and providing substantially a 180 degree phase shift in signal voltage through the channel. The neutralizing circuit is arranged to include said phase shifting network and the interelectrode capacity of the tube to prevent energy interchange between the grid and anode circuits of the amplifying tube in the said signal amplifying channel.

The invention is therefore particularly adapted for use in certain types of power amplifiers comprising parallel-connected amplifier tubes coupled at the output through an impedance inverting network, the tubes being biased to provide normal and peak signal amplification without overload.

An amplifier of this type is known generally as a high efficiency linear amplifier and was described by W. H. Doherty in the September 1936 issue of the Proceedings of the Institute of Radio Engineers, vol. 24, No. 9, beginning at page 1163.

This amplifier is a power amplifier for amplitude modulated waves and is provided with two amplifying channels, in one of which, the main amplifier channel, an amplifier tube is biased substantially to cut-off, and in the other of which channels, the peak amplifier channel, the amplifier tube is biased beyond cut-off so that it comes into operation only on the peaks of the signals exceeding the carrier level.

An impedance-inverting network connected between the output circuits of the two tubes is arranged to present an impedance at the input end which is inversely proportional to the terminating impedance thereof. As soon as the peak amplifier comes into action in parallel with the load, it raises the effective terminating impedance of the impedance-inverting network, with a consequent lowering of the impedance presented to the main amplifier, and resulting in a sharing of the peak load by both tubes.

55 A neutralizing system embodying the inven-

tion may be applied to an improved high efficiency linear amplifier of the type above referred to, as shown, described, and claimed in my copending application Serial No. 166,508, filed September 30, 1937, for a High efficiency linear amplifier; and assigned to the same assignee as this application. In that application a 90° phase-shifting network and the impedance-inverting network are employed in the main channel, the phase shift being arranged to be accumulative, whereby the total carrier phase shift is substantially 180° between the input and the output circuits of the main amplifier channel.

In the peak amplifier channel, a corresponding 180° phase-shifting network is provided, which has a characteristic such that its effect upon the phase shift of a modulation envelope may be the same as that of the main channel. It has been found to be desirable to neutralize this channel in certain amplifiers of the high efficiency linear type to prevent flow of current in the plate or output circuit back to the input circuit and energy exchange between said circuits.

It is, therefore, an object of the present invention to provide an effective method and means for neutralizing the peak amplifier channel of an amplifier of the type referred to, which may include and advantageously utilize the 180° phase-shifting network and preclude the necessity for tapped grid or plate inductances.

It is a still further object of the present invention to provide a neutralizing circuit for a high efficiency linear amplifier having two amplifying channels, one of which includes a tube biased beyond cut-off and the other of which includes a tube biased to cut-off, wherein the first named amplifying channel includes a 180° phase shifting network and a neutralizing circuit including said network and the inter-electrode capacity of said tube in said channel.

It is also an object of the present invention to provide a high efficiency linear amplifier of the type comprising parallel connected amplifier tubes coupled at the output through an impedance inverting network, in which one of the tubes biased beyond cut-off for peak amplification, is neutralized through a circuit including a 180° phase shifting network and the inter-electrode capacity of the tube connected therewith.

In the drawing to which attention is now directed, the invention is illustrated by way of

example, in connection with a two-channel amplifier of the type shown in my copending application hereinbefore referred to, the figure being a schematic circuit diagram of such an amplifier, embodying the invention.

Referring to the drawing, a modulated carrier wave amplifying channel for a transmitter or other high power amplifier device carrying a modulated wave signal is provided by two amplifying channels B and C of a high efficiency linear amplifier containing the amplifying tubes 5 and 6, respectively, having a common output anode circuit 7 and a common modulated signal input circuit 8.

15 The tube 5 is arranged to be biased substantially to cut-off, while the tube 6 is biased beyond cut-off, the operation being such that the channel B containing the tube 5 provides the carrier wave amplification and the down modulation, while the channel C carries the peaks and the up modulation, and through its operation permits the channel B to function to carry an increased load.

20 The output circuit of tube 5 is provided with a tuned circuit or tank 9, and is coupled to the output circuit of the tube 6 through an impedance-inverting network 10, which may be of any suitable and well-known type. When the 25 impedance of the output circuit 7 increases, resulting from the tube 6 carrying load, the impedance is reflected back to the output circuit of tube 9 and inverted, that is, lowered to such an extent that the tube 5 may carry a heavier load.

30 This permits the tube 5 to increase its power output without increasing its plate voltage swing. When the tube 6 comes into operation in parallel with the load through the circuit 7, it raises the effective terminating impedance of the network 10 with a consequent lowering of the impedance presented to the tube 5, whereby the 35 tube 5 will carry an increased portion of the load because of the apparent lowered load impedance presented to it through the impedance-inverting network.

40 It will be seen that both tubes 5 and 6, or both channels of the amplifier, receive energy from the input circuit 8. From the foregoing description, it will be seen that it is desirable and necessary for the proper operation of the 45 amplifier that the two halves of the modulation envelope shall be in phase at the output circuit 7. Accordingly, a 90° phase-shifting network 11 is inserted in the grid or input circuit 12 of one tube and is arranged to add an additional 90° carrier phase shift to the 90° carrier phase shift resulting from the signal passing through the 50 impedance-inverting network 10, so that the 55 output voltages of the two channels will be in phase.

60 Having obtained a 180° carrier phase shift between the modulated signal input circuit and the common output or anode circuit 7, instead of compensating one 90° phase shift by means 65 of the other, a corresponding 180° carrier shift network is provided in the peak amplifier channel C and is arranged to include means for causing a phase shift of the sidebands and a phase delay 70 in the halves of the modulation envelope which are the same as that caused by the networks and tuned circuits in the main or carrier amplifier channel. This 180° phase-shifting network is connected, as indicated within the bracket 15, in 75 the input or grid circuit of the tube 6 and between

the tube and the input circuit 8. It will be noted that the 180° phase-shifting network 15 comprises two 90° networks 16 and 17 in cascade across the signal channel C containing the tube 6, and that between said networks there is interposed a tuned circuit or tank 18, with a similar tuned circuit or tank 19 provided adjacent to the tube 6, following the second 90° phase-shifting network 17. The circuits 18 and 19 serve to increase the input impedance of the network at 10 the tube 6.

15 In the present example, the two channels are coupled through the common input circuit 8 and an output transformer 22 to a modulator stage comprising an R. F. amplifier 20 and a modulator 21. The primary 23 of the input transformer is tuned and connected to the output circuit of the modulating stage.

20 The common anode or output circuit 7 for the two channels is likewise tuned to the carrier and 25 is coupled through a transformer 25 with an antenna or other load circuit 27, for the amplifier. Any other suitable output coupling may be provided which complies with the arrangement for the high efficiency amplifier wherein 25 the impedance-inverting network is interposed between the anode circuits of the two amplifier channels.

30 It will be noted that the networks 11 and 10 may have a positive or a negative sign in regard 35 to the phase shift, and likewise the networks 16 and 17 in the other channel may have a positive or a negative sign, but in any case, whether the shift is positive or negative, the sum of the phase shift in the one channel, that is, in the networks 11 and 10, must be the same as the sum of the phase shift in the networks 16 and 17, whereby the output from both channels may combine in the common output circuit 7 and may be applied to the load circuit 27 in phase.

40 By utilizing the 180° network 16 and 17 in the peak amplifier channel C, neutralizing of the 45 system may be accomplished by connecting the input high potential terminal 30 of the 180° phase shift network with the anode circuit 31 of the peak amplifier tube 6 through a neutralizing 50 capacitor 32. This arrangement provides a 55 circuit in which the direction of current flow is reversed in the two capacities provided by the neutralizing capacitor 32 and the inter-electrode capacity 33 of the tube 6 as a consequence of the action of the 180° network 16 and 17. If the magnitude of the capacitor 32 is properly adjusted there will be no flow of current through the anode circuit 7 of the tube 6 back to the input circuit and, consequently, no energy interchange between the grid and plate circuits. The flow of current is indicated by the arrows.

60 The capacity of the capacitor 32 is adjusted to equal $C_N = \alpha C_{gp}$ in which α is the ratio of the signal input to the signal output voltage of the network 16-17 and the tube 6 and C_{gp} is the grid-to-plate capacity of the tube 6.

65 The neutralizing connection is such that the input side of the 180° phase shifting network is coupled through the capacitor 32 to the anode end of the output circuit of the tube whose grid is supplied with signal energy from the 180° phase shifting network.

70 I claim as my invention:

75 In a high efficiency linear amplifier comprising two parallel amplifying channels, the combination with an amplifier tube in each channel, of means providing a common output anode circuit 75

for said tubes, a load circuit coupled to said anode circuit, means providing an impedance inverting network interposed between said tubes in the anode circuit, means providing a 180° phase shifting network in the grid circuit of one of said tubes, and means for neutralizing the amplifying channel including said tube comprising a

neutralizing capacitor connected between the input end of said phase shifting network at the high potential side thereof and said common output anode circuit at the output end of said impedance inverting network.
